TRACK EXTENSION AND CLAMPING MEANS
THEREFOR

Kenneth M. Lane, Gate City, Va., assignor, by direct and mesne assignments, of one-fourth to James C. Vann, Abingdon, Va., and one-fourth to Will H. Nickels, Gate City, Va.

Application May 7, 1934, Serial No. 724,390

5 Claims. (Cl. 238—10)

This invention relates to a track extension and clamping means therefor.

In mines, in particular, it is often desirable to extend a track quickly, whereby a car may be loaded with greater convenience and ease, and therefore, my invention relates particularly to novel means for extending a track beyond the main or primary track.

An object of the invention is the provision of simple and efficient clamping means for holding rails of an auxiliary track securely in an adjusted position against the rails of the primary or permanent track.

Another object of my invention is the provision of simple and efficient clamping means, beyond the primary track, for engaging the extension or auxiliary track and fastening the same securely to a tie of the roadbed.

A still further object of my invention is the construction of a novel auxiliary clamping device, which engages the rail, or rails, of the extension or auxiliary track, and which clamping device is fixedly secured by preferably a spike through a tie; this clamping device eliminating a number of ties and a number of spikes, performing in itself, the function of the same.

With the foregoing and other objects in view, my invention comprises certain novel constructions, combinations and arrangements of parts as will be hereinafter fully described, illustrated in the accompanying drawing, and more particularly pointed out in the appended claims.

In the drawing:

Figure 1 is a top plan view of the structure in accordance with the present invention.

Figure 2 is a sectional view taken on line 2—2, Figure 1, and looking in the direction of the arrows.

Figure 3 is a sectional view taken on line 3—3, Figure 1, and looking in the direction of the arrows.

Figure 4 is a perspective view of the primary clamping device.

Figure 5 is a perspective view of the auxiliary clamping device.

Referring to the drawing by numerals, 1 designates the primary track and 2 is the extension or auxiliary track, both resting upon the roadbed 3 which includes the ties 4.

The primary track comprises the fixed rails 5 secured by spikes 6 to the ties 4. The auxiliary track comprises the rails 7 laid on their sides, with the tread of the rails bearing against the webs of the permanent or fixed rails 5, as clearly shown in Fig. 2. In this manner, the wheels 8

of a car passes from the permanent rails 5 onto the rails 7 of the track section 2, with their flanges 9 riding on the web of rails 7, as shown in Fig. 3.

By the employment of my invention, the rails 7 do not have to be cut or shortened for enabling the operator to construct the extension quickly, since I cause said rails 7 to slidably engage the permanent rails 5, and hold said rails 7 in an adjusted position by primary clamping devices 10.

Each device 10 comprises a claw bolt 11 having at its outer end a bifurcated claw 12, and being threaded at its inner end; the inner end extends through the lower portion of eye bolt 13. A nut 14 secures eye bolt 13 upon the claw bolt 11, and

said nut also serves to cause the claw 12 to tightly engage the tread of rail 5 as clearly shown in Fig. 2. The upper end of eye bolt 13 is threaded, and mounted on this end is auxiliary jaw 15. This jaw resembles an ordinary plate, but has a novel downwardly-extending bifurcated edge 16, into which edge fits one edge of the base of the rail 7 of the auxiliary track 2, Fig. 2. A nut 17 is threaded on the upper end of eye bolt 13 and by means of which nut jaw 15 is caused to tightly engage the base of rail 7. Consequently, the base of rail 7 is clamped between the claw bolt 11 and jaw 15. The rails 5 and 7 are clamped between the claw 12, eye bolt 13 and jaw 15, Fig. 2. I

preferably use two of the primary clamping devices 10 on each two engaging rails 5 and 7, Fig. 1. This produces a very durable structure for holding said rails in an adjusted position, since the rails 7 are slidably adjustable against the sides or webs of rails 5.

It is necessary to anchor or fasten, beyond the ends of rails 5, the rails 7 of the auxiliary track. Therefore, to efficiently accomplish this, and to save time as well as eliminate a number of ties and correspondingly a number of spikes, I use my efficient auxiliary clamping device 18. This device comprises claw bolt 11, with the claw 12 turned downwardly, as shown in Fig. 3. Mounted on claw bolt 11 is primary jaw 19. This primary jaw 19 comprises a vertical body 20 having a right angled flanged upper end 21 and a bifurcated outwardly-extending flanged end 22.

In the bifurcation of end 21, I place preferably a spike 23. The head of the spike rests upon end 22, with most of its shank in the bifurcation. The claw 12 of the claw bolt 11 of this device is hooked under the head of the spike and then by tightening on nut 23a, the bolt is tightly engaged, preventing creeping or displacement of rails 7, and only requiring one clamping device 18 beyond the end of the primary track 1, for each

rail 7. This is a very simple and efficient fastening means for the auxiliary or extension track, whereby it is secured to a single tie.

In the clamping device 10, the claw 12 on claw bolt 11, constitutes the rail-clamping or engaging element, whereas in the clamping device 18 the jaw 19 on claw bolt 11 constitutes the rail-clamping or engaging means.

While I have described the preferred embodiment of my invention and illustrated the same in the accompanying drawing, certain minor changes or alterations may appear to one skilled in the art to which this invention relates during the extensive manufacture of the same, and I, therefore reserve the right to make such changes or alterations as shall fairly fall within the scope of the appended claims.

What I claim is:

1. In a device of the class described, the combination of a claw bolt provided with means for clamping a portion of a rail, an eye bolt slidably mounted on said claw bolt, a jaw for clamping a portion of a rail on said eye bolt, a nut on said claw bolt against said eye bolt, and a nut on said eye bolt against said jaw.

2. In a device of the class described, the combination of a claw bolt provided with means for clamping a portion of a rail, an eye bolt slidably mounted on said claw bolt, a plate-like jaw provided with a downwardly-extending bifurcated edge for receiving a portion of a rail, said jaw mounted upon said eye bolt, a nut on said eye bolt against said jaw, and a nut on said claw bolt against said eye bolt.

3. In a device of the class described, the com-

bination of a claw bolt provided at one end with a claw, a jaw on said claw bolt contiguous to said claw, said claw and jaw adapted to receive a portion of means for securing the claw bolt and jaw to a rail, and rail engaging and clamping means on said claw bolt.

4. In a device of the class described, the combination of a claw bolt provided at one end with a bifurcated claw, a jaw on said claw bolt contiguous to said claw, said jaw provided with a lower outwardly-extending bifurcated end registering with the bifurcated claw, and means at the other end of said claw bolt for engaging and clamping a portion of a rail.

5. In a device of the class described, the combination of a claw bolt threaded at one end and provided at its other end with a bifurcated claw, a primary jaw comprising an elongated body mounted upon said claw bolt, said body provided at its upper end with an inwardly-extending extension for clamping against a portion of a rail and at its lower end with an outwardly-extending bifurcated extension, said bifurcated extension registering with said bifurcated claw, whereby a spike may be gripped between said extension and claw, an eye bolt slidably mounted on the threaded end of said claw bolt, a nut on said threaded end of the claw bolt against said eye bolt, an auxiliary plate-like jaw on the upper end of said eye bolt, said auxiliary jaw provided with a bifurcation at one end for receiving a portion of a rail tread, and a nut threaded upon the upper end of said eye bolt against said auxiliary jaw, substantially as shown and described.

KENNETH M. LANE. 35
